Primary Examiner — Marie D. Fast Horse

(57) **CLAIM**

The ornamental design for a base unit for a communications device, as shown and described.

DESCRIPTION

FIG. 1 is a front-top-left perspective view of a base unit for a communications device showing my new design;

FIG. 2 is a back-bottom-right perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines depict portions of the base unit for a communications device that form no part of the claimed design.

1 Claim, 8 Drawing Sheets
